UNITED STATES PATENT OFFICE.

GEORGE B. CORAM AND JOHN C. CORAM, OF LOWELL, MASSACHUSETTS,
ASSIGNORS TO THE DENNIS CASH CARRIER COMPANY, OF SAME PLACE.

CASH AND PARCEL CARRIER AND TRACK FOR SAME.

SPECIFICATION forming part of Letters Patent No. 286,592, dated October 16, 1883.

Application filed August 31, 1883. (No model.)

To all whom it may concern:

Be it known that we, GEORGE B. CORAM and JOHN C. CORAM, of Lowell, in the State of Massachusetts, have invented certain new and useful Improvements in Cash or Parcel Carriers and Tracks for the Same, of which the following is a specification.

Our invention has relation, first, to means for shunting or diverting the cash-carrier from one track to another, in which respect it is an improvement on shunting mechanism for devices of the type shown and described in Letters Patent No. 278,226, dated May 22, 1883; and, secondly, to means for supporting the track-rails and for holding them in proper position relatively to one another; and it will be described in the order just indicated by reference to the accompanying drawings, in which—

20 Figure 1 is a plan view of a portion of a store-track, intended to illustrate to a certain extent, diagrammatically, the first portion of our invention. Fig. 2 is an enlarged end elevation of one of the main flanged diverting-blocks. 25 Fig. 3 is a front elevation of one of the track-supporting hangers, showing the rails in cross-section and the carrier in elevation. Fig. 4 is a side elevation of the same, partly in section. Fig. 5 is a side view of two rails, showing the 30 fastening fingers or projections on their meeting or abutting ends. Fig. 6 is a front elevation of one of the cross-rods for spacing and staying the track-rails, which latter are shown in section.

35 The first portion of our invention, which refers to the means for shunting or diverting the carrier from one track to another, and contemplates the combination for this purpose of a flanged carrier and a stationary diverting-flange to co-operate therewith, substantially in accordance with the plan set forth in Letters Patent No. 278,226, is fully illustrated in Figs. 1 and 2. In these figures, A is the main track, B C are side tracks, and B' B'' C' C'' are branch 40 tracks from B and C, respectively. D D' D'' E are carriers. Under our improvement we provide the carriers with a peripheral flange, a, to engage the stationary diverting-flange c for the purpose of shunting the carrier from 45 the main track A onto its appropriate side

tracks, B or C, and with a peripheral flange, b, to engage the stationary diverting-flange d for the purpose of shunting the carrier from its side track onto its appropriate branch track B' or B'', &c. The flange a, which, for convenience' sake we term the "main flange," is of greater diameter than the flange b, which may be termed the "branch flange." The difference in size between them may be varied; but in practice we usually make the main flange about 55 one-eighth of an inch greater in diameter than the branch flange, and we set the stationary diverting-flange which is to co-operate with the main carrier-flange at such an elevation that, while it can be reached by the latter, it cannot be engaged by the smaller or branch carrier-flange b. Thus the main-track stationary diverting-flange c cannot be reached by the flange b, and consequently we are enabled to put both sets of carrier-flanges a b upon the 60 body of the cash-carrier, between its wheels or flanged ends x, without danger of the branch carrier-flanges b interfering with the main-track diverting-flange c. By varying the position of the carrier-flanges a b and correspondingly varying the position of the stationary diverting-flanges c d, a carrier can be shunted from the main track onto its appropriate side track, and thence onto its appropriate branch track. For example, the carriers 65 D D' D'' have their main flanges a placed to engage the diverting-flange c, by which they will be shunted onto side track B; but the branch flange b is set on carrier D' to shunt the carrier onto branch track B', on carrier 70 D'' to shunt the carrier onto branch track B'', and on carrier D to shunt the carrier onto a branch track beyond branch B''. On the other hand, carrier E has its main flange a so placed that it passes by without engaging the 75 stationary diverting-flange c at the junction of tracks A and D, and does not act until it reaches the stationary diverting-flange c at the junction of tracks A and C, which it engages with the effect of shunting carrier E onto side track C, from which latter the carrier will be shunted onto one or the other of the branches C' C'', according to the position of its branch flange b. The stationary diverting-flanges 80 may be placed either above or below the car- 85

riers. We prefer to place them below, as shown. They are secured in position by suitable means, being usually attached to the hangers which are placed at intervals along 5 the line to support the track. We in some instances, particularly for the main track, make these flanges of blocks as shown on enlarged scale in Fig. 2, which are grooved on top, as shown, for the purpose of furnishing a guide 10 for those carriers which are not to be shunted onto the particular side track at whose junction with the main track the block is placed.

The second portion of our invention is illustrated in Figs. 3 to 6, inclusive. With a view 15 to secure the track to the hangers by which it is upheld, we provide the track-rails with fingers or projections, which can be bent into or around the hanger, thus fastening the rails firmly in place. In practice we form apertures 20 in the hanger, through which the fingers are first passed, and then are bent over and clinched upon the hanger, and we prefer to have these fingers on the rails at their meeting or abutting ends, so that when the fingers 25 are passed through and clinched upon the hanger not only will the rails be held tight to the hanger, but the abutting ends of the two rails will be held closely and firmly together. We also, with a view to staying and spacing 30 the two parallel rails of which the track is composed, combine with the track cross stay- rods, whose ends are formed to clasp the body of the rail, and are provided with shoulders which fit over corresponding shoulders on the 35 rails, so as to hold the rails securely in place in the socket-like ends of the stay-rods without requiring the use of solder or any other extraneous means of fastening the two together. A stay-rod of this character affords a con- 40 venient and effective means of preventing the track from spreading or closing, and can be applied very easily by slipping it onto the ends of the rails, and then pushing it along thereon to its proper place. The track-rails 45 shown in the drawings are made of sheet metal, and have a **U** form in cross-section—a convenient form to permit of the use of side and branch tracks in conjunction with the main track—as indicated in Fig. 1. The flanged end 50 or wheels *x* of the carrier run in these trough-like rails, and with a view to suppressing noise, as well as other reasons, we prefer to groove the periphery of the wheels *x* and to apply thereto tires *x'*, composed of rubber of cylindrical cross-section, as indicated in Fig. 55 3, where one of the tires is shown in section. The hanger consists of a frame, *F*, of usual or convenient shape, which is suspended from a rod, *F'*, attached to the ceiling or other suitable part of the room in which the apparatus 60 is set up. The lower cross-piece of the frame is grooved at *e*, so as to receive the track-rails, which fit in grooves *e*, as indicated in Fig. 3. The hangers are usually applied at the points 65 where the ends of rails meet, and such is the case in the drawings, the abutting ends of the rails *G G* resting in the cradles or grooves *e*,

formed for them in the hanger. Each rail has at its ends the finger or prong (lettered *f*) hereinbefore referred to. In the arrangement 70 shown in the drawings (which is the preferred arrangement) holes or passages *g* lead down from the cradles or grooves *e* through the hanger. When the ends of the two rails are put together, the prongs *f* pass down through 75 the holes *g*, and are then bent outwardly and clinched, thus holding the two ends of the rails together and binding them to the hanger. These prongs can be formed separately from the rails and attached to them, or they may 80 be made in one piece therewith. One of the cross stay-rods for spacing and holding the track-rails in place at points intermediate between the hangers is represented at *H* in Fig. 6. It is formed at each end with a groove 85 or cradle of the proper size and shape to receive and fit snugly upon or around the body of the rail, and with one or more lips or shoulders to overlap a corresponding shoulder or shoulders on the rail. As the rail in this in- 90 stance is of **U** form, the cradle or grooves *h* of the stay-rod are of corresponding shape, and at the top or upper end of these grooves are lips or shoulders *i*, placed at such height as to allow the upper edges of the rail to just 95 pass beneath them. The width of these shoulders *i* does not exceed the thickness of the walls of the **U**-shaped rail, so that they do not interfere with the carrier-wheels which run in the rails. The stay-rod, of course, is of such 100 length that when in place it will hold the two sides of the track the proper distance apart. To apply the stay-rod, it is fitted upon the ends of the rails, and is then slipped along thereon until it has reached its proper place. When 105 thus placed, it serves to space the track and to prevent it from closing or opening, while, owing to its peculiar construction, there is no need of using solder or any other extraneous means of fastening it to the rails. In case these stay- 110 rods are used with rails provided with prongs *f*, the prongs are bent up in line with the rails, or thereabout, so as to permit the stay-rods to be slipped over them onto the rails, after 115 which the prongs can again be turned down; or, in case the prongs are made separate from the rails, they need not be attached thereto until after the stay-rods are put in place.

Having set forth the nature of our improvements and the best way now known to us of carrying the same into practical effect, what we claim as new and of our own invention is—

1. The combination, with the main, side, and branch tracks, of a carrier provided on that portion of the body between the track-rails 125 with a main flange and a branch flange of less diameter than the main flange, a stationary main-track diverting-flange placed at such elevation as to be reached only by the larger or main carrier-flange, and a side-track diverting-flange for shunting the carrier from the side to the branch track, substantially as and for the purposes hereinbefore set forth.

2. In a store-service track, the combination,

with track-supporting hangers, of track-rails provided with fingers or prongs adapted to be bent over upon or around the hangers, substantially as and for the purposes hereinbefore set forth.

3. The combination, with track-supporting hangers provided with passages or holes, substantially as described, of track-rails provided with fingers or prongs adapted to pass through said holes and to be then bent around or clinched upon the hanger.

4. The combination, with a track-supporting hanger, of rails whose abutting or meeting ends rest in or on the hanger, and are provided with prongs which pass through holes in the hanger and are bent around or clinched upon the hanger, substantially as and for the purposes hereinbefore set forth.

5. The combination of U-shaped rails provided with end projections or prongs, with hangers through which said prongs pass and are clinched upon the hangers, substantially as hereinbefore set forth.

6. In a store-service track, the combination, with the track-rails, of cross stay-rods provided with ends adapted to fit around or upon the body of the rails, and with lips or shoulders which overlap shoulders on the rails and serve to confine said rails in their seats or cradles in the stay-rods, substantially as and for the purposes hereinbefore set forth.

7. In combination with the U-shaped track-rails, the cross stay-rod provided with end grooves or cradles, *h*, and lips or shoulders *i*, substantially as and for the purposes hereinbefore set forth.

In testimony whereof we have hereunto set our hands this 30th day of July, 1883.

GEORGE B. CORAM.
